UNITED STATES PATENT OFFICE.

RINALDO VITI, OF ST. LOUIS, MISSOURI.

SWITCHING MECHANISM.

1,168,922.

Specification of Letters Patent. Patented Jan. 18, 1916.

Application filed November 18, 1914. Serial No. 872,706.

To all whom it may concern:

Be it known that I, RINALDO VITI, a citizen of the United States, residing at 1012 Holland Building, St. Louis, State of Missouri, have invented certain new and useful improvements in Switching Mechanism, of which the following is a specification, reference being had therein to the accompanying drawing.

10 This invention relates to improvements in railroad switches, especially intended for use in mines where an easily movable switch is needed, and more particularly to that type of switch designed to be operated from an 15 engaging part carried by a moving vehicle so as to dispense with the services of a switchman.

The invention contemplates the provision 20 of instrumentalities enabling the throwing of a switch point when the vehicle is moving, in one direction, and enabling the restoration of said switch point to its original position by a continued movement of the vehicle in the same direction.

25 The invention also embraces means for reinforcing the switch point when open to relieve the mountings thereof of the strains incident to travel over and against said switch points, said means also acting to assist in the maintenance of switch points in 30 operative thrown position.

The features of construction constituting 35 my present improvements generally referred to above will be more apparent from an inspection of the accompanying drawings, forming a part hereof and wherein the preferred embodiment of the invention is illustrated, when considered in connection with the detail description thereof as hereinafter 40 contained.

In the drawings: Figure 1 is a plan view 45 of a section of track illustrative of a main line and a branch line leading therefrom, with my switching mechanism coöperating therewith; Fig. 2 is a longitudinal section on the line 2—2 of Fig. 1; Fig. 3 is a transverse sectional view on the line 3—3 of Fig. 1, and Fig. 4 is an elevation of a fragmentary portion of a vehicle, for example, a conventional motor car or locomotive, showing the switch controlling device mounted upon and adapted to travel with said car to effect the operation of the switch throwing mechanism, in keeping with the purposes of the motorman or engineer.

Referring more specifically to the drawings wherein like reference characters designate corresponding parts in the several views, A represents the main line of a railroad and B the branch line leading therefrom.

C indicate the usual switch points associated with the lines referred to and pivoted at D to permit lateral movement thereof as occasion requires.

The free or pointed ends of the switch points are pivotally united, as at E, to a cross bar F, designed to throw the points in unison so that when one point is engaged with its coöperating rail G, the other is carried from its corresponding coöperating rail H.

The means for laterally shifting the connecting bar F may now be defined.

J are a pair of bell crank levers, pivoted at their elbows to a tie member or equivalent supporting structure K, the pivoting of the bell crank levers being on the outwardly projecting ends of the supporting member K, as represented at L.

Arranged parallel to the straight rail H of the main line, and at suitable distances, respectively, in rear and in advance of the switch points, are a pair of actuators M and M', the same being in the nature of rocking cams arranged horizontally, whereby to swing vertically, and formed of undulating metal bars, as shown. These cams are pivoted, as at N, in a pair of separated brackets O, P, mounted on supporting beams o, p, similar to the supporting member K, the pivoting of the cams being with the axes thereof disposed in a horizontal plane to permit the swinging of the cams in a vertical plane, as previously mentioned. Depending portions Q, rigidly connected to the cams, so as to rock therewith, are connected by oppositely extending links R and S to the outer ends of the bell crank levers J.

From the description thus far given, it will be seen that a car moving in the direction of the arrow, along the main line and operating the cam Q' on the right hand side of the track will depress the same throwing the extension of the cam rearwardly, effecting a corresponding movement of the links and bell crank levers, so that the bar F is shifted also in the direction indicated by the arrow and the switch closed to permit the car to continue along the main line, the sub-

sequent action of the cam M along the main track, restoring the switch points to an open position, if desired.

In view of the fact that the cams, mountings and connecting means associated therewith are of the same general construction, on opposite sides of the track, it is not necessary to again specifically define the construction of these cams. During the operation of the device, if it is desired to send the car around the curve, the trip U carried by the car is shifted to engage the cam M' on the left hand side of the track, causing the cam member to tilt and through the medium of the connecting links S shift the switch points to permit the car to move along the branch line, the switch points being restored to a closed position by the actuation of the cam R' arranged along the branch line.

In view of the fact that the cams, mountings and connecting means associated therewith are the same at the opposite sides of the road, it is not necessary to again specifically define the elements making up the corresponding pair of cams and operating means adjacent to the branch line, because as stated, they are substantially identical with the same operating means along the main line, it being sufficient here to say that one double cam M' is arranged adjacent to the main line in advance of the pointed ends of the switch points and another R' adjacent to the branch line, so that by actuation of one of the cams the throwing of the switch points in one direction is accomplished, and by an actuation of the other cam of that pair the switch points may be restored to the initial position.

Intermediate of the free ends of the switch points and on the supporting member K, I pivotally mount at S', a pair of bell crank levers, the inner ends of which are connected by a strong bar T, while the outer ends are turned upwardly to constitute abutting shoulders adapted to engage the inner surfaces of the switch points. These bell crank levers are rocked by the engagement of the switch points therewith in consonance with the movement of the switch points and serve to reinforce the open point against lateral strains and to maintain the closed point in contact with its rail, as will be obvious to persons skilled in the art.

Any suitable device or devices may be employed in connection with the engine or car for engaging with the appropriate cams, but I prefer to use a horizontally mounted and shiftable rod U, the ends of which may be projected in opposite directions to engage and ride over the cams desired, the rod being pivoted to a vertically disposed pivoted lever V adapted to be held in either a neutral or either one of its lateral positions by a pawl and ratchet mechanism W.

It will be understood that independently of the direction of travel of the train or car by reason of the double cam actuators, the projection of the rod to one of its lateral positions will first throw the switch and if the rod is permitted to retain the same position, it will engage the other cam of the pair being controlled for the time being and restore the switch to its original position.

While I have herein disclosed one special embodiment of the invention, it will be apparent that the latter is capable of embodiment in such other forms and devices as may be in keeping with the hereto appended claims.

Having thus described the invention, what is claimed is:

1. In combination with a main and branch line of a railroad, pivoted switch points coöperating therewith, means for throwing the switch points to opposite positions, and means unattached to the points and independent of said throwing means for riding against and reinforcing the free ends of the switch points, said reinforcing means comprising pivoted means freely associated with the switch points and adapted to be shifted by the movement of the latter and consisting of a pair of pivoted levers mounted independently of the switch points, each having one arm abutting against the switch points and the other arms thereof being connected together, substantially as and for the purpose described.

2. The combination with a main and branch line of a railroad, pivoted switch points coöperating therewith, means for throwing the switch points to opposite positions, a plurality of members unattached to the switch points and one member lying adjacent each point and independent of the switch throwing means for reinforcing the ends of the switch point, and connecting means for said reinforcing members whereby they act in unison, substantially as and for the purposes described.

3. The combination with a main and branch line of a railroad, pivoted switch points coöperating therewith, means for throwing the switch points to opposite positions, and members independent of said throwing means arranged adjacent each switch point for reinforcing the free weakened ends of the switch points, said reinforcing members comprising pivoted levers having a connecting member therewith so that they act in unison, movably associated with the switchpoints and adapted to be shifted by a movement of the latter, substantially as and for the purpose described.

4. The combination with the main and branch line of a railroad, pivoted switch points coöperating therewith, means for throwing the switch points to opposite positions, a reinforcing member lying adjacent

each switch point and adapted to bear against the weakened ends of the points, a connecting member arranged between the reinforcing members and connected therewith, whereby the reinforcing members act in unison, the said reinforcing members adapted to be shifted by a movement of the switch points.

5. The combination of a main and branch line of a railroad, pivoted switch points co-operating therewith, means for throwing the switch points to opposite positions, and means unattached to the points and independent of said throwing means for riding 10 against and reinforcing the ends of the switchpoints, said reinforcing means comprising pivoted bell crank levers each having an arm associated with a switch point and adapted to be shifted by the movement 15 of the latter, a connecting rod arranged between said levers and connected to one of their arms whereby the levers move in uni-

son upon the actuation of the switch points, substantially as described.

6. The combination of a main and branch line of a railroad, pivoted switch points co-operating therewith, means for throwing the switch points to opposite positions, and means comprising a pivoted lever arranged adjacent each switch point for reinforcing 25 the same, the said levers being provided with a relatively wide upstanding arm adapted to ride against the switch points, and a connecting member arranged between the levers whereby the said levers act in unison, substantially as and for the purposes 30 described.

In testimony whereof I hereunto affix my signature in the presence of two witnesses.

RINALDO VITI.
